FIG. 3.

INVENTOR.
Nelson W. Colgrove,
BY
Horatio E. Bellevue
ATTORNEY

UNITED STATES PATENT OFFICE.

NELSON W. COLGROVE, OF PROVIDENCE, RHODE ISLAND.

HAT.

1,378,444.

Specification of Letters Patent. Patented May 17, 1921.

Application filed September 18, 1920. Serial No. 411,305.

To all whom it may concern:

Be it known that I, NELSON W. COLGROVE, a citizen of the United States, residing at Providence, in the county of Providence and 5 State of Rhode Island, have invented certain new and useful Improvements in Hats, of which the following is a specification.

My invention relates to headgear provided with sweat bands.

10 I have discovered that the reason why the body or crown of the hat is discolored by perspiration is because the latter travels through the perforations made by the threads which unite the sweat band to the 15 body.

The essential objects of my invention are to prevent such discoloration, and to effect this end in a simple and inexpensive manner, and without the use of a multiplicity 20 of auxiliary strips.

To the above ends essentially my invention consists of such parts and such combinations of parts as fall within the scope of the appended claims.

25 In the accompanying drawings which form a part of this specification—

Figure 1 is a vertical section of a hat embodying my invention,

Fig. 2, a similar enlarged section of a portion of the same, and

Fig. 3, an elevation of the face of the sweat band adjacent the hat body.

Like reference characters indicate like parts throughout the views.

35 In the embodiment of my invention herein illustrated 5 is a hat body or crown, 6 the brim, and 7 the usual ribbon. The usual sweat band 8 of leather, skin, or other usual similar material is provided. A strip of oil

40 silk, rubber tissue, or other suitable water-proof material is applied to the band as follows. The body 10 of the strip rests against the inner face of the sweat band with its upper and lower lateral margins 12 folded

45 or wrapped over the lateral edges of the band 8 and resting against the outer face of the latter. The adjacent portions of the flaps or folds 12 are united by stitching 14. The described parts are engaged by stitching

50 or stitches 16 which is engaged through the band 8, the lower fold 12, and the body

5 only. It is obvious that the latter stitching is performed prior to the application of the ribbon 7, and before the completion of the wrapping of the water-proof strip upon the 55 sweat band. It will be observed that the stitches 16 are not accessible by perspiration because of the interposition of the water-proof portion 10. Also but one strip of material auxiliary to the sweat band is required 60 to carry out my invention, and that the application of said strip is easily effected. My invention is adapted also to embodiment in any ordinary hat without any reconstruction or reorganization of the parts. The 65 wrapping strip 10, it will be further noted, is smooth and unbroken throughout its area affording a smooth and agreeable contact with the wearer's head.

It will be understood that in the showing 70 of the illustrations the thickness of all the parts is exaggerated.

I claim:

1. In a hat, a body, a sweat band, a strip of water-proof material embracing the 75 inner face of the band comprising integral flaps overlapping the outer face of the band and in contact with said body, and stitches engaging the body solely through the sweat band and one flap.

2. In a hat, a body, a sweat band, a strip of water-proof material embracing the face of the band provided with integral flaps overlapping the outer face of the band, 80 stitches engaging the body solely through the sweat band and one flap, and stitches connecting the flaps.

3. In a hat, a body, a sweat-band, and a strip of water-proof material applied to said band with the body of the strip resting 90 against the inner face of the band with its upper and lower lateral margins folded over the lateral edges of the band and resting against the outer face of the latter, and means uniting the adjacent edges of the 95 folds of said strip, leaving the inner face of the said strip entirely disconnected from the said uniting means.

In testimony whereof I have affixed my signature.

NELSON W. COLGROVE.
